UNITED STATES PATENT OFFICE.

LOUIS MARGOLIS, OF ALLENTOWN, PENNSYLVANIA, ASSIGNOR TO FIFTH AVENUE CORSET COMPANY, INC., OF ALLENTOWN, PENNSYLVANIA, A CORPORATION OF NEW YORK.

CORSET-MEASURING FRAME.

Application filed April 17, 1922. Serial No. 553,548.

To all whom it may concern:

Be it known that I, Louis Margolis, a citizen of the United States of America, and a resident of the city of Allentown, county 5 of Lehigh, and State of Pennsylvania, have invented certain new and useful Improvements in Corset-Measuring Frames, of which the following is a specification.

The object of this invention is to provide a 10 frame which may be adjusted to a person's body and measurements read therefrom which will enable a corsetière to manufacture through the guidance of such measures a properly fitting corset.

15 Further objects are to provide a frame which is adjustable while on the body, which will permit of such measurements, as girth around the hips, that can only be made while the person is standing, but in which 20 the frame will also admit of such measurements as need to be taken in a sitting posture, such as the distance from the waist to the groins.

In the accompanying two sheets of drawings which form a part of this specification:

Figure 1 is a front view of a measuring frame constructed in accordance with this invention,

Fig. 2 is a rear view of the same,

30 Fig. 3 is a perspective of one of the slides which carry the bust and hip measuring bands,

Fig. 4 is a horizontal section through one of the fasteners for the measuring bands,

35 Fig. 5 is a perspective of the upper end of one of the vertical ribs,

Fig. 6 is a perspective of one of the extensions to the vertical ribs, and

Fig. 7 is a top view of one of the pairs of 40 straps for binding against the body the lower ends of the front ribs.

The frame comprises a waist-measuring band *a*, a bust-measuring band *b*, and a hip-measuring band *c*. A fastener or clamp is 45 attached to one end of each of these bands. It comprises a trough *d* with a pivoted clamp *e*, between which and the trough is passed the other end of the band. The bands are suitably graduated to indicate the girths 50 at the ends of the fasteners. The end of the waist-band with its attached fastener is attached to a middle front rib *f*. Side front ribs *g*, *g* and back ribs *h*, *h* each have connections fixed on the ribs consisting of

tongues *i*, *i* under which the waist band is 55 threaded and the ribs are adjustable along the waist-band but the position is fixed on each band at which the waist band crosses. Slides *j*, *j* engage all of the ribs above the waist-band and the back ribs below the waist- 60 band. They carry folded over tongues *k*, *k* under which the bust-measuring bands and the hip-measuring bands are threaded. The slides are adjustable vertically on the ribs, and there is horizontal adjustment between 65 the slides and the bands excepting the slide on the middle front rib to which one end of the bust measuring band and its fastener are attached. The ends of the slides *m*, *m* are indicating points against graduations *n*, *n* 70 on the ribs which show the distance of the bust-measuring band above the waist-measuring band and the distance of the hip-measuring band below the waist-measuring band. The sides of the ribs at their tips are 75 bent over to form tongues *p*, *p* which engage extensions *r*, *r* at the upper and lower ends of the ribs. The ends of the extensions which overlap the ribs have eyes *s*, *s* which encircle the ribs, and the outer ends of the 80 extensions carry buttons *t*, *t* by which the extensions can conveniently be drawn out. The ends *u*, *u* of the ribs are indicating point against graduations *v*, *v* on the extensions which show the distance to the ends of 85 the extensions above or below the waist-band. Pairs of straps *w*, *w* joined at their ends are each detachably connected at one end to a slide *x* on the middle front rib, and at their other ends have eyes *y*, *y* into which 90 the ends of fabric tapes *z*, *z* connect. The side front ribs are passed between the straps of each pair. All of the parts except these fabric tapes are preferably of flexible sheet steel such as is used for surveyors' tapes or 95 for corset bones.

The application of the measuring frame to the body for measuring will be clear from the drawings. The vertical ribs are adjustable horizontally on the bands and they are 100 spaced and located where desired. If fewer bones are desired in the corset than there are ribs in the measuring frame then some of the ribs may be paired as shown in the front view. The spacing of the bands is 105 also adjusted so that they will all lie over the bust, waist and hips where it is important to take the measurements. While standing,

the bands are drawn up to the desired degree of snugness and clamped. The upper extensions are then drawn up to determine the upper margin of the corset where each bone comes. In order to be assured that the measurements are also correctly indicated for a properly fitting corset when seated, the hip band is first released and the pairs of straps with attached fabric tapes are depended on to bind the lower ends of all of the ribs, as these straps can be adjusted sufficiently above the groins. The extensions at the lower ends of the ribs are then drawn down to determine the lower margin of the corset where each bone comes.

The foregoing detailed description has been given for clearness of understanding and no undue limitation should be deduced therefrom but the appended claims should be construed as broadly as permissible in view of the prior art.

What I claim, is:—

1. In a corsetière's measuring frame, waist, bust, and hip measuring bands each 25 having a fastener at one end thereof, back ribs connected with the waist, bust and hip measuring bands, a middle front rib, side front ribs, extensions for the ribs, connections between the ribs and the waist and 30 bust measuring bands, and separate means for binding the lower ends of the side front ribs to the body to be measured.

2. In a corsetière's measuring frame, waist, bust, and hip measuring bands each 35 having a fastener at one end thereof, back ribs connected with the waist, bust and hip measuring bands, a middle front rib, side front ribs, extensions for the ribs, connections between the ribs and the waist and 40 bust measuring bands, and straps each of which is connected at one end to the middle front rib for binding the lower ends of the side front ribs to the body to be measured.

3. In a corsetière's measuring frame, 45 waist, bust, and hip measuring bands each

having a fastener at one end thereof, back ribs connected with the waist, bust and hip measuring bands, a middle front rib, side front ribs, extensions for the ribs, connections between the ribs and the waist and 50 bust measuring bands, and pairs of straps each connected at one end to the middle front rib and having the lower ends of the side front ribs engaged between them and thereby bound to the body to be measured. 55

4. In a corsetière's measuring frame, waist, bust, and hip measuring bands each having a fastener at one end thereof, back ribs, a middle front rib, side front ribs, connections fixed on the ribs and adjustable 60 along the waist measuring band, slides at the upper ends of all of the ribs and at the lower ends of the back ribs, a connection between the slide at the upper end of each of the ribs and the bust measuring band, and 65 a connection between the slide at the lower end of each of the back ribs and the hip measuring band.

5. In a corsetière's measuring frame, waist, bust, and hip measuring bands each 70 having a fastener at one end thereof, back ribs, a middle front rib, side front ribs, connections fixed on the ribs and adjustable along the waist measuring band, slides with 75 indicating points at the upper ends of all of the ribs and at the lower ends of the back ribs, a connection between the slide at the upper end of each of the ribs and the bust measuring band, a connection between the slide at the lower end of each of the back 80 ribs and the hip measuring band, and graduations on each of the ribs for indicating at the indicating points of the slides the distances of the bust measuring band above and of the hip measuring band below the 85 waist measuring band.

Signed at Allentown, Pa., this 13th day of April, 1922.

LOUIS MARGOLIS.
